UNITED STATES PATENT OFFICE.

JULIA LOLA SOLOMONOFF, OF NEW YORK, N. Y.

TOE-DANCER'S SHOE.

Application filed March 31, 1925. Serial No. 19,605.

To all whom it may concern:

Be it known that I, JULIA LOLA SOLOMONOFF, a citizen of the United States, and a resident of the city of New York, in the 5 county of New York and State of New York, have invented certain new and useful Improvements in a Toe-Dancer's Shoe, of which the following is a specification.

This invention relates to a toe dancer's 10 shoe, more particularly that type of shoe where, in the execution of certain dance steps, the performer is poised upon the extreme toe portion of the foot.

In an article of this kind where support 15 is usually obtained to some extent from the sole portion thereof, it has been found necessary to build the sole portion of several layers, and to that add sufficient rigidity in a longitudinal direction to give the necessary support and bracing effect to the arch 20 of the foot. As a result it has been found that the vertical stresses thus given to the sole of the shoe will disrupt the laminations of the sole, lose the bracing effect to the 25 arch and distort the general contour of the shoe itself.

I have found that the necessary support 30 and bracing effect to the arch of the foot when a ballet dancer's or toe dancer's shoe 35 is used in the toe position, may be retained, that the disruptive tendency may be avoided, and the general shape or contour of the shoe itself retained, if the sole portion of the shoe is formed arcuately, or further, if it is formed so that any bending 40 tendency is towards the direction of the sole of the foot and not away from it.

The object, generally of my invention, 45 therefore, resides in the provision of a toe dancer's or ballet dancer's shoe adapted to be used in a normal way, and for dancing on the toe position, having a built-up sole structure avoiding the use of materials which will lend discomfort and confined principally to leather or the like and retaining the stiffness necessary in use, without the introduction of wood or metal parts.

A further object of my invention is to 50 arcuately form the sole portion of the shoe so that when used in the toe position, the bracing effect will be retained and disruptive tendencies between the several laminations of the sole thereof overcome.

A further object of my invention resides 55 in the provision of means for retaining the arcuate form of the sole of the shoe.

A still further object of my invention resides in the provision of a stiffening sole for a toe dancer's shoe formed arcuately and associated therewith of means to retain such 60 arcuate formation.

I have further found that "layoffs" in 65 dancing or discontinuous practice of dancing of the toe type variety, and also walking on French heels, has had detrimental effects upon the muscles of the leg, particularly the tendons which have a tendency to shorten or become set in such position. I have found that the requisite movement 70 of the foot from the flat position to the toe position may be materially facilitated by maintaining the sole of the shoe in an arcuate form and raised somewhat from the floor level position.

I have further found that by associating 75 a heel with a toe dancer's shoe, particularly one arcuately formed, and of a size which covers a substantial portion of the sole of the shoe, that the movement from the flat position to the toe position may be effected 80 with considerable ease, and at the same time the introduction of such heel member retains the necessary stiffness of the sole to give the bracing effect in a transverse longitudinal direction when used in the toe position, and that where the sole is formed of 85 laminated layers, a separation or displacement thereof will be prevented as well as distortion of the contour of the shoe itself.

A further object of my invention resides 90 in the provision in a toe dancer's shoe of a heel member; further in the provision of a heel member arcuately maintaining the sole of a toe dancer's shoe, and further 95 of a size covering a material portion of the sole so as to maintain the same in an arcuate form.

To attain these objects or such further 100 objects as may appear herein or be hereinafter pointed out, I make reference to the accompanying drawing forming a part hereof, in which—

Fig. 1 is a plan view of a toe dancer's shoe with portions in section;

Fig. 2 is a side elevation of a toe dancer's 105 foot in the toe position with my invention shown in section.

Fig. 3 is a plan view looking in the direction of the sole partly broken away to disclose the layers.

Referring particularly to the drawing, 110 10 is a shoe proper, the outer portion of top

thereof being preferably made of fabric material 12 which may be satin, silk, leather or the like, the lining material 13 finished off at the edge by tape 14 which is formed to have a drawstring 15 for adjustment and tightening, which will be apparent. At the toe portion 16, I preferably introduce between the several layers padding material 17 to build the same up, and in the illustration shown such padding material 17 is interposed between the toe point 19 and the turned under inner sole 21 which is stiffened leather arcuately formed to assume an extremely arched formation similar to a highly arched foot. To the inner sole thus formed, there is attached an additional stiffening sole 22, also arcuately formed, and is attached thereto by adhesive and staples or nails 24 in a suitable manner. This sole or stiffening member so formed serves to hold the box toe layers at 25.

In my preferred form, the stiffening sole 22 is split along its rearmost portion at 27 to form an upper layer 28 and a lower layer 29. Between the several layers thus formed, there is interposed a member 30 which is shaped at its uppermost portion 31 similar to the arcuate formation of the arch of the shoe, preferably shaped, and is to take on the form of a heel. The split portion 29 of the stiffening member is attached to the foremost portion of the heel at 32 and is turned over the bottom face at 33 and affixed by adhesives such as glue or nails or a combination thereof. Over this turned over layer, there is affixed a wear layer, preferably a sheet of leather 34. The shoe top layer 12 may be tucked underneath the upper layer 28 and the top portion of the heel 30.

Although above, I have described the stiffening layer 24 as made up of a split rearmost portion, it will be observed that I may also form the same of two separate layers combined in any suitable way at the portion in front of the heel, between which the heel is interposed, and although I have described the means for maintaining the arcuate position by a heel, I also contemplate making such arcuate stiffening means of dimensions less than that customarily worn.

It will be observed that a shoe of the nature herein described when used in the toe position as illustrated in Fig. 2, in which view 35 is the foot and 36 the toe, and the skeleton thereof 37 is shown in phantom. By reason of the shoe being strapped firmly upon the foot, sufficient frictional contact is obtained, so that in the toe position a bracing effect is had when thus used in a vertical position. The sole being arcuately formed when resting upon the toe position, will bear against the sole or arch of the foot and any vertical stresses imparted to the sole when used in a vertical position will be displaced against the arch of the foot rather

than from it. And where the outer sole of the shoe is of different length at the toe portion than the inner sole, tending to cause a displacement of the laminations when the foot is in the toe position by the arrangement herein, the several layers or laminations of the shank or sole of the shoe will not be severed from each other, but will have the tendency to be forced against each other and therefore be retained together against displacement.

In use in the transverse position, the layers or sole portion will have additional stiffening effect due to the fact that it cannot be displaced from the position against the sole of the foot, the arcuate formation being retained by reason of the method in which the layers are combined, or as in the preferred form when the heel is attached. This latter construction further makes this type of shoe serve a double purpose, particularly when used in performances wherein characters other than the customary ballet dance is portrayed, such as for instance, Spanish effects or Mexican effects, wherein "heel and toe turns" are to be executed by the dancer.

This type of heel shoe in connection with a toe of the character above described, makes it readily possible for the dancer to assume the toe position without any difficulty, particularly where the softened toe increases the frictional engagement with the floor and the heel of the foot has been raised to some extent from the ground by the heel member attached to the shoe. This has been found particularly desirable and useful to toe dancers who have had occasion to discontinue dancing for any period so that their muscles or tendons are not as pliable as when flexed to the fullest extent, and have become somewhat shortened due to non-use. The aid derived in having the foot assume a position off the floor aids materially therefore to assume the toe position as well as giving the desirable novel costume appearance.

Having fully described my invention, what I claim as new and desire to cover by Letters Patent, is

1. In a toe dancer's shoe, wherein the sole is used as a compression member in a longitudinal direction, the combination therewith of a bracing member in the form of a heel, serving to maintain the arcuate conformation of the sole and to prevent displacement of the several laminations of the sole structure.

2. In combination, in a toe dancer's shoe having a toe portion adapted to support the foot for executing a dance step in the toe position, of a stiffened arcuately shaped laminated sole, said laminated sole having a member in the form of a heel arcuately formed so as to maintain the sole portion

against the sole of the foot when used in the toe position.

3. In combination, in a toe dancer's slipper having a toe portion adapted to be used for executing dance steps in the toe position, of a stiffened sole arcuately shaped, said sole being split along the rearward portion thereof, and a member interposed between such split portions in the form of a heel for maintaining said sole portion in an arcuate conformation.

4. In combination, in a toe dancer's shoe having a toe portion adapted to support the

foot for executing a dance step in the toe position, of a stiffened arcuately shaped sole therefor, comprising laminated portions one of which is divided along a portion of its length, forming a bridge member serving to maintain said sole in arcuate conformation and a heel member between said divided portion to retain said bridge member and sole in arcuate conformation. 15

In witness whereof, I have signed and sealed this specification, this 9th day of December, A. D. 1924.

(Mrs.) JULIA LOLA SOLOMONOFF.
